JOHN B. MULLALLY AND GEORGE L. GRANT, OF SEATTLE, WASHINGTON.

CLIP-ATTACHING DEVICE.

1,077,154.

Specification of Letters Patent.

Patented Oct. 28, 1913.

Application filed October 23, 1912. Serial No. 727,373.

To all whom it may concern:

Be it known that we, JOHN B. MULLALLY and GEORGE L. GRANT, citizens of the United States, residing at Seattle, in the county of King and State of Washington, have invented a certain new and useful Improvement in Clip-Attaching Devices, of which the following is a specification.

Our invention relates to improvements in devices for attaching spring-wire clips to a plurality of papers, such as bills, letters, manuscripts and the like, which are to be clasped or clamped together, and the object of our improvement is to provide a simple, reliable and inexpensive tool that may be disposed on one's desk where it may be operated conveniently to affix one or more of such clips to a plurality of papers to clamp them together, such tool being adapted to receive and hold a plurality of said clips in a position from which successively they each may be attached to papers in response to the operation of the mechanism of said tool.

We attain such object by devices illustrated in the accompanying drawings wherein—

Figure 1 is a plan view of a structure embodying our invention wherein some of its parts are indicated by broken line, Fig. 2 is a view of the same in longitudinal and vertical section on broken line $x-x$ of Fig. 1, Fig. 3 is a like view, on like section of Fig. 1, showing some of its moving parts in a position that they assume at one stage of their operation, Fig. 4 is a view in perspective of a movable part of our invention, Fig. 5 is a perspective view of some of the fixed parts of the same, Fig. 6 is a fragmentary view partly in vertical-section on broken line $y-y$ of Fig. 1 showing a modified form of one detail of our invention and an additional part that may be desirable under some conditions of use, and Fig. 7 illustrates a form of spring-wire clip which is adapted to be attached to papers by the operation of our invention.

Like reference numerals indicate like parts throughout the drawing.

Referring to the drawings, 8 is a hollow base of cast-metal, as of cast-iron, upon which are mounted two guide-plates 9 secured by screws 11, said guide-plates 9 being

placed parallel with each other and at a suitable short distance apart. An upright bracket 10 is disposed vertically to bridge across the space between the guide-plates 9 with its side braces 12 and the ends of its bottom fastened to said guide-plates 9, as shown more clearly in Fig. 5. On that side of bracket 10 opposite the braced side is a vertical web 13, which is integral with said bracket 10, and which serves to support a vertical shaft 14 of diamond shaped cross-section whose lower end is suitably higher than the top surface of guide-plates 9 to permit a clip 15 (of a form shown in Fig. 7) to pass between it and said guide-plates 9, the cross-sectional shape of said shaft 14 adapting it better to receive and conduct downwardly a plurality of said clips 15 which may be deposited thereon, ready for use, the bottom one of which clips 15, normally lower than the bottom of said shaft 14, rests on the top of the base 8 between the guide-plates 9, the guiding flanges 16 of said guide-plates 9 being cut away each side to permit a clip 15 to drop from shaft 14 to base 8 while guided on its way by the edges of angular pieces 17 which edges project inwardly to engage with the angular members respectively of a clip 14. A slide-plate 17 having flanges 18 extending from each side of its bottom and provided with a V shaped notch 19, one end of which extends inwardly to a parallel sided slot 20 and further provided with a projecting knob 21, adapted to serve as a handle, as most clearly illustrated in Fig. 4, is disposed to slide freely within the space between the guide-plate 9 with its flanges 18 in engagement with the flanges 16 of the guide-plates 9, as shown in Fig. 1. In the base 8 is a longitudinal slot 22 disposed beneath the slide-plate 17, and extending through said slot 22 from the underside of said base 8 and into the slide-plate 17 at a point not far from the knob 21, is a shouldered screw 23 which may traverse said slot 22 as the slide-plate 17 is moved back and forth between the guide-plates 9 and to such shouldered screw 23 is connected an extended end 24 of a spiral spring 25 whose other extended end 26 is fastened to the base 8 by a screw 27, as seen more clearly in Fig. 2, wherein the slide-plate 17 and said spring 25 with its extended

ends 24 and 26 are shown in their normal positions, and such positions also are indicated in Fig. 1, while Fig. 3 shows such parts in the positions they assume when the 5 slide-plate 17 is moved to the full extent of its travel toward the bracket 10, thus when the slide-plate 17 is moved by the knob 21 in one direction to the end of its travel and thereupon released then the retractile force 10 of the spring 25 may serve to move said slide-plate 17 in the opposite direction back to its normal position shown in Figs. 1 and 2.

Disposed on base 8 midway between the 15 guide-plates 9 is a fixed arm or cam 28 whose upper edge surface inclines gradually, for a suitable distance, and then in a line parallel with the top surface of base 8 for a distance nearly to the ends of the 20 guide-plates 9 while the surface of its under edge rises in an abrupt curve to a straight line which is parallel with and of suitable distance from the line of its upper edge to form a rigid prong, as shown in Fig. 2, beneath which the end portions of a plurality 25 of papers 29, as shown in Fig. 3, may be inserted between such prong and the top surface of the guide-plates 9 and when such papers 29 are thus disposed and when a clip 30 15 is conducted downwardly by the shaft 14 to rest on the base 8 beneath said shaft 14, then by moving the slide-plate 17 toward the cam 28 such clip 15 travels toward the right with its free ends 30 beneath the 35 flanges 16 of the guide-plates 9 to a point where the apex 31 of the clip 15 engages with the top edge of cam 28 to raise that portion of clip 15 and its continued movement causes such portion to ride on the top 40 of said cam 28 to its end there to fall downwardly on to the papers 29 to clamp them between said apex portion 31 and the free end portions 30 whereupon the slide-plate 17 may be released to be carried back by the 45 spring 25 to its normal position which position permits a next succeeding clip 15 to fall in front of it ready to be attached in a like manner to clamp together other papers.

In Fig. 6 we have shown a screw 32 projecting from the top of clip-holding shaft 14 upon which a threaded-nut 33 may be screwed, if it be desired, to prevent any of the clips 15 from falling off the shaft 14 in case of an accidental tipping over of the 55 instrument or of accidental inversion of it when handling it. Also in Fig. 6 we have shown how a cam 34 may be swingingly hinged to the base 8 in substitution for the fixed cam 28 of Figs. 1, 2 and 3. Such cam, 60 when employed, normally may rest in an upright position, as indicated by dotted lines in Fig. 6, whereby a larger number of papers may be disposed with their ends against said cam 34 and when a clip 15 is 65 carried forward by the slide-plate 17 then

the apex 31 of the clip 15 may push against the cam 34 to force it down on to said papers and, continuing its motion, slide to the end of such cam 34 thence to fall on to such papers to clamp them against the free ends 70 30 of the clip 15 whereupon the cam 34 is free to move backward to its normal position and the papers may be removed. The swinging back to such normal position of the cam 34 may be caused by pushing 75 against it the edges of papers that are to be fastened together or by automatic means, not shown, which will readily suggest themselves to one skilled in the art, as, for instance a retractile spring.

Manifestly adequate changes in the form and size of parts of our invention may be made to adapt it to any one of many forms and sizes of clips and clamping devices without departing from the spirit of our invention.

What we claim is:

1. In a clip attaching device, the combination with a base member, of movable means associated with such base member 90 and adapted to engage with and move a clip that is provided with an upper and a lower clamping member, guiding members associated with said base member and adapted to guide said movable means, means for spreading said clamping members of said clip in response to a movement of said slide-plate and means for receiving and guiding a plurality of such clips to such a position with relation to said movable means that 95 said movable means may engage with the lowermost of such clips to move it into engagement with a plurality of papers to clamp them together.

2. In a clip attaching device, the combination with a suitable supporting base, of a guide structure extending upwardly therefrom and adapted to guide clips downwardly, a member movable horizontally on said supporting base to feed the lowermost 10 of said clips along, and means associated with said supporting base for spreading the upper and lower members of such clip as it is fed along.

3. In a clip attaching device, the combination with a base member, of a movable slide-plate associated with said base member and adapted to engage with and move a clip, two guiding members secured to said base and adapted to guide said slide-plate 11 in its movements, retractile means for moving said slide-plate in one direction, means associated with said base for separating the clamping members of a clip as said clip is moved by said slide-plate, and means 1 for guiding clips to a point where successively they may engage with said slide-plate to be moved thereby.

4. In a clip attaching device, a base member, a guide structure extending upwardly 1

therefrom, a plurality of clips in said guide structure, said clips having upper and lower clamping members, a member movable horizontally along the base member to feed the lowermost clip along, and means on the base member to spread the upper and lower members of each clip as it is fed along.

In witness whereof, we hereunto subscribe

our names this 30th day of September A. D., 1912.

JOHN B. MULLALLY.
GEORGE L. GRANT.
